[57] CLAIM

The ornamental design for combined lid and utensil holder, as shown and described.

DESCRIPTION

FIG. 1 is a front elevational view of a combined lid and utensil holder of my claimed design;
FIG. 2 is a rear elevational view thereof;
FIG. 3 is a left side elevational view thereof, the right side elevational view being a mirror image thereof;
FIG. 4 is a top plan view thereof;
FIG. 5 is a bottom plan view thereof;
FIG. 6 is a perspective view thereof, the lid and utensil shown in hidden line are not part of the claimed design; and,
FIG. 7 is a side elevational view thereof in a collapsed state.
